THADDEUS R. GOLDSBOROUGH, OF WILKINSBURG, PENNSYLVANIA, ASSIGNOR TO
WESTINGHOUSE ELECTRIC & MANUFACTURING COMPANY, A CORPORATION OF
PENNSYLVANIA.

PRESSURE-DISTRIBUTING DEVICE

Application filed August 6, 1927. Serial No. 211,065.

My invention relates to pressure-distributing devices, and it has particular relation to diaphragms for telephone receivers, loud speakers, phonographs, and the like.

5 With only few exceptions, devices intended for sound reproduction embody some sort of vibratile diaphragms, either of small dimensions associated with horns, or of relatively great areas which directly act upon the 10 air without the intervention of horns or analogous devices.

Diaphragms of the latter type have been made of many different materials, such as paper, laminated wood, balsa-wood, spun 15 aluminum, and the like, and have assumed many different forms varying from flat to conical, in the effort to secure the greatest rigidity commensurate with the mass thereof.

It has also been proposed to construct a 20 diaphragm of a pleated sheet of paper, by arranging the pleats, or corrugations radially, and by so distorting them that the diaphragm varies progressively, in flexibility, from a stiff central portion toward the 25 periphery thereof. Pleated diaphragms are exemplified by the patent to Lumiere, No. 1,036,526, and it is to them that the present invention particularly relates.

Pleated paper diaphragms made according 30 to the teachings of the Lumiere patent are quite satisfactory when the power input to the actuating means therefor is kept low, but they are decidedly prone to rattle and to radiate buzzing sounds when forced to vibrate with large amplitudes.

I have established, by research and experiment, that the unpleasant sounds accompanying the reproduction of speech and music by the usual pleated paper diaphragm is principally, if not entirely, caused by the flexing 40 of the radial elements and by their vibratory contact with one another when the diaphragm is actuated.

It is, accordingly, an object of my invention to provide an improved diaphragm of the pleated type that is sufficiently rigid from the center to the periphery to ensure that the elements thereof will not flex when the diaphragm is subjected to driving forces applied at the center.

Another object of my invention is to provide an improved diaphragm of the pleated type in which none of the elements thereof are in objectionable vibratory contact with each other when the diaphragm is actuated.

Another object of my invention is to provide a diaphragm of the pleated type in which driving forces are carried from the center to the periphery thereof along salient angles formed by the intersections of the 55 faces of the pleats.

Another object of my invention is to provide a corrugated diaphragm of novel shape which, when in vibration, is damped to some extent by radial air-currents which are constrained to flow between the individual 60 corrugations.

Another object of my invention is to provide a novel configuration for a diaphragm or other object stamped, embossed, or molded 65 from relatively thin material, that will have maximum stiffness relative to the mass thereof.

According to one modification of my invention, I attain the aforementioned objects 70 by so modifying the peripheral contour of a pleated diaphragm made from a folded and scored portion of paper, parchment or analogous material that each individual corrugation is capable of transmitting force 75 from the center of the diaphragm to the circumference thereof through beam-action, and is prevented from flexing by a plurality of 80 spacing elements.

According to another form of my invention, a flat circular portion of ductile material such as mild steel, aluminum, or the like, is embossed or stamped into the same configuration that is given to a pleated paper diaphragm when it is constructed according to the 85 method that will later be described in detail. By reason of the fact that the rigidity of a circular portion of material is vastly increased by being stamped, or corrugated, according to my invention, such stamped or 90 embossed articles may be very successfully utilized as diaphragms, or as bearing members for building foundations, as strain-distributing, or anchoring devices for maintaining 95 guy-wires and the like imbedded in the 100

earth, or as means for distributing a load over any sort of semi-solid or plastic material.

Among the novel features of my invention 5 are those particularly set forth in the appended claims. The invention itself, however, both as to its organization and its method of operation, together with further objects and advantages thereof, will best be 10 understood from a consideration of the following description of a specific embodiment, taken in connection with the accompanying drawings, in which:

Figure 1 is a rear elevational view of a 15 pleated diaphragm constructed according to a preferred embodiment of my invention,

Fig. 2 is a cross-sectional view taken along a line corresponding to the line II-II of Fig. 1,

Fig. 3 is a cross-sectional view taken along a line corresponding to the line III-III of Fig. 1,

Fig. 4 is a front elevational view, and

Fig. 5 is a view of a portion of paper or 25 parchment that has been scored preparatory to being folded according to my invention.

Referring specifically to Figs. 1, 2 and 3, my improved diaphragm comprises a plurality of approximately trough-shaped corrugations 1 radiating from a central hub 2, the corrugations being defined by a plurality of alternately disposed ribs 3 and depressions 4, the ribs on one side of the diaphragm corresponding to the depressions on the other 35 side thereof. The ribs on both sides of the diaphragm, for the major portion of their radial length, lie in parallel planes, and diverge progressively from the hub toward the periphery.

As a point 5, lying a short distance inwardly from the periphery, the ridges on one side of the diaphragm bend downward from the plane in which lie the major portions thereof and terminate in a plane parallel to 45 the first mentioned plane and intermediate between it and the plane in which lie the major portions of the ridges on the other side of the diaphragm. The ridges, therefore, although not lying in a single plane, are substantially continuous from the hub to the 50 periphery. As shown in Fig. 4, the ridges on the other side of the diaphragm merge into a plurality of triangular elements 6, bounded by ridges 7 and 8, the peripheral boundaries 55 of which lie in the intermediate plane referred to above, and which are tangential to the surface of an imaginary conical surface 11 having its apex in the axis 12 of the diaphragm.

The merging of the ridges into the triangular elements 6 is a result of the novel method of scoring and folding I have invented, and gives rise to a diaphragm having very marked advantages over folded diaphragms 65 known to the prior art.

Forces originating in the electromagnetic actuating means (not shown) which may be coupled to the central hub by any suitable means, are transmitted to the periphery of the diaphragm by what might be termed 70 "beam-action" of each radial corrugation. In other words, by reason of the fact that the ribs on one side of the diaphragm extend in a substantially unbroken line from center to periphery, and, by reason of the merging 75 of each rib on the other side into two diverging ribs defining a triangular bracing element, each rib behaves as though it were a reinforced girder, or beam, and does not buckle when forces are applied to either end thereof. The diaphragm, as a whole, therefore, can not buckle under forces applied at the center if the peripheral ends of the separate ribs are prevented from spreading. The spreading of the ribs is prevented by affixing 80 of a mounting rim 13, preferably made of material slightly stiffer than the material from which the diaphragm itself is made, to the elements 6.

According to one method of practicing my 90 invention, a diaphragm having the superficial configuration just described may be formed from a single rectangular sheet of paper, parchment, or the like, by folding or pleating it in the manner indicated in Fig. 95 5. The length of the strip of material before scoring and folding should be approximately twice the circumference of the finished diaphragm, while the width thereof should be substantially equal to the radius of 100 the finished diaphragm.

Referring specifically to Fig. 5, the lines 15, 16 and 17 represent creases presenting salient angles to the observer when the sheet is viewed from above, and the lines 18, 19, 105 20 and 21 represent re-entrant angles when viewed from the same position. Small triangular portions 22 of the material, bounded by the lines 23 and 24 and the edge of the strip, are then preferably removed, and the 110 ends of the strip are then brought together and secured.

At this stage of the forming operation, the diaphragm presents the appearance of a cylinder having fluted sides. The perimeter 115 of one end of the fluted cylinder is next pressed inwardly toward the axis thereof, and then downwardly along the axis, forcing the material to assume a relatively flat circular shape wherein the fluted elements or 120 ribs lie radially of the axis of the cylinder, the sides of said elements being closest together at the center and gradually diverging toward the perimeter where they meet at a 125 more obtuse angle.

The peripheral termination of each alternate rib is then folded inwardly and downwardly along the scored lines 15 and 16, and the triangular surfaces 25 and 26 bounded by the lines 15, 19 and 23 and 16, 19 and 24, 130

respectively, are firmly cemented together. The hub element 2 is next inserted into the small opening defined by the central ends of the ribs, and cemented in place. The dia-
5 phragm has now assumed the configuration clearly shown in Figs. 1 to 4 of the drawings. Small washers 27 may be slipped over each end of the hub, these washers being cemented to the inner ends of the ribs, in order to bet-
10 ter distribute thereto the actuating forces.

The exact length of the scored lines 15, 16, 18 and 20 may be left largely to the judgment of the manufacturer, although I have found it preferable to make them equal to
15 each other.

A diaphragm constructed according to my invention has many advantages over pleated diaphragms known to the prior art. Perhaps the most pronounced advantage lies in
20 the fact that, even when made from extremely light and flexible material, it assumes a configuration which gives it sufficient rigidity to prevent flexing when it is suspended from a flexible mounting annulus and subjected to
25 driving forces applied at the hub. Each element of the radial corrugations is so braced that it is prevented from flexing, and the tendency to nodal vibration substantially eliminated.

30 Although the primary object of my invention is to provide a method whereby an extremely rigid diaphragm may be made by scoring and folding a single sheet of flexible material in a novel manner, my invention, in
35 so far as the configuration of the finished dia- phragm is concerned, is equally applicable to diaphragms that are constructed by embossing, stamping or molding. The peculiar manner in which the individual corrugations are
40 terminated at their peripheral ends adds ma- terially to the strength of the finished prod- uct, and may very advantageously be utilized in the forming of bearing members for foun- dations, or for devices intended to distribute
45 stresses and strains over a mass of semi-solid material.

Although I have shown only a single form of my invention, and have described only such form and a modification thereof not involving the folding of a strip of flat material, my invention is not to be restricted thereto, but is to be limited only by the prior art and by the spirit of the appended claims.

I claim as my invention:

55 1. A pressure-distributing device having a plurality of radial corrugations the projec- tions of which, on a plane parallel to said device, are quadrilaterals.

60 2. A pressure-distributing device having a plurality of radial corrugations the projec- tions of which, on a plane parallel to said device, are quadrilaterals, the peripheral angles of said quadrilaterals being sepa- rated by substantially triangular figures.

65 3. A pressure-distributing device having a

plurality of radial corrugations the projec- tions of which, on a plane parallel to said device, are quadrilaterals, the peripheral angles of said quadrilaterals being separated by substantially triangular figures and the 70 peripheral sides of said figures being sectors of a circle in which lie said peripheral angles.

4. A pressure-distributing device having a plurality of radial corrugations adapted to transmit force from the center of said device 75 to the periphery thereof through beam- action, the projection of each corrugation upon a radial plane being chisel-shaped, the points of said chisel being peripheral.

5. A pressure-distributing device having a 80 plurality of radial corrugations adapted to transmit force from the center of said device to the periphery thereof through beam- action, the radial edges of said corrugations on one side of said device merging into radially extending edges lying at an angle to said first-mentioned edges, and the radial edges of adjacent corrugations on the other side of said device merging into radially extending and approximately triangular-shaped sur- 85 faces lying at an angle to said radial edges.

6. A pressure-distributing device having a 90 plurality of radial corrugations, the peripheral terminations of said corrugations simu- 95 lating triangular pyramids.

7. A pressure-distributing device having a 95 plurality of radial corrugations, said corrugations being braced against deformation.

8. A pressure-distributing device having a 100 plurality of radial corrugations, the peripheral terminations of said corrugations simu- 100 lating triangular pyramids and the peripherally-lying apices of said pyramids being separated by triangular integral elements.

9. A pressure-distributing device having a 105 plurality of radial corrugations, the peripheral terminations of said corrugations simu- 110 lating triangular pyramids and the peripherally-lying apices of said pyramids being separated by triangular integral elements lying approximately tangential to a conical surface.

10. A pressure-distributing device having a 115 plurality of radial corrugations, the peripheral terminations of said corrugations being spaced by integral triangular elements lying in the surface of a conical figure the apex of which is positioned in a line perpendicular to a plane defined by the peripheral sides of any two of said triangular elements.

11. A pressure-distributing device having a 120 plurality of radial corrugations defined by radial salient and re-entrant angles, the salient angles lying in a plane parallel to the re-entrant angles, and the re-entrant angles, 125 when viewed from one side of the device, merging into triangular elements.

12. The method of forming a relatively 130 rigid pressure-distributing device from a rectangular sheet of flexible material, which

comprises pleating said sheet along lines perpendicular to the longest dimension thereof, affixing the ends of the sheet together, flattening out the cylinder so formed, forming a 5 re-entrant fold in the peripheral termination of alternate pleats, and affixing together the edges of said folds, whereby the peripheral

terminations of said pleats are spaced apart by approximately triangular elements that lie in a pyramidal surface to which a mounting annulus may be affixed.

In testimony whereof, I have hereunto subscribed my name this 29th day of July, 1927.

THADDEUS R. GOLDSBOROUGH.
